UNITED STATES PATENT OFFICE.

P. G. WOODARD, OF WATERFORD, PENNSYLVANIA.

BUTTER-WORKER.

Specification of Letters Patent No. 31,758, dated March 19, 1861.

To all whom it may concern:

Be it known that I, P. G. WOODARD, of Waterford, in the county of Erie and State of Pennsylvania, have invented a new and 5 Improved Machine for Working Butter; and I do hereby declare that the following is a full and exact description thereof, reference being had to the accompanying drawings, making part of this specification.

10 Figure 1, is a view of the machine in perspective; Fig. 2, a plan of the same; Fig. 3, a view, in partial section, of a part detached, showing, on a larger scale, the details of its construction.

15 Like letters designate corresponding parts in all the figures.

The special objects of my invention are to produce a machine for working butter, perfectly efficient in action, yet of the 20 most simplicity of construction, in respect to cheapness, the use of suitable material and that readily at hand, and with tools the most ordinary, and in hands, if necessary, but little skilled.

25 In regard to material, the machine, with two or three unimportant exceptions, is composed wholly of wood, which is in all respects well suited to the purpose. How the machine is thus enabled to be constructed almost entirely of wood, with gearing movements, will be apparent from the description following. Almost any wood possessing no exceptionable qualities, may be used; and thus the material is near at hand in every 35 locality.

A simple rectangular frame A, of the desired size and proportions, serves to mount all the working parts upon. The board, or table H, on which the butter is to be placed 40 for working, is arranged in the frame substantially as shown, so that one, projecting end shall be lower than the other, in order that the butter-milk may quickly flow off and be caught in a receptacle placed for the 45 purpose. This inclination is effected by having one of the cross-pieces of the frame, on which the butter board rests, somewhat higher than the other, or by shortening two of the legs of the frame A, as shown in the 50 drawings. Channels, or gutters m, m, in the top of the butter board serve to conduct the buttermilk to the proper place for discharging.

The working of the butter is accomplished 55 by means of a fluted roller E, passing over it by a reciprocating rolling movement, and

kept pressed down into it while moving forward and backward. The ridges i, i, of the roller thus continually indenting channels in the butter and these in the direction of 60 the inclination of the butter board, allow the butter-milk to flow out immediately, as fast as expressed from the butter. The reciprocating traveling and rolling movement is given to the roller E, by causing its journals s, s, to roll on two horizontal supporting pieces C, C, stretching across the sides of 65 the machine; and in order that it may keep firmly in place, and not slip on the supporting pieces, its journals s, s, are provided 70 with radial pins f, f, projecting therefrom at regular distances around their peripheries, so as to enter corresponding rows of holes e, e, in the supporting pieces C, C, so that the pins of each journal thus serve as 75 the cogs of a pinion, and the holes as the cogs of a rack. The pins are made a little pointed and the holes somewhat flaring, so that they may work freely together. The roller is turned forward and backward by 80 means of a winch G, or its equivalent.

Since the fluted roller E, is made of wood, and is therefore comparatively light, and since it is required to press with considerable force upon the butter, it is necessary to 85 hold it firmly down upon its rack supports C, C. I accomplish this by means of horizontal bars D, D, situated over the rack supports C, C, parallel therewith, and at such a distance therefrom as to just allow 90 the journals s, s, of the roller to pass freely between.

In order to enable the roller E, to be readily removed for washing it, &c., the bars D, D, are respectively pivoted at one end, on 95 posts d, d, while the other end is held down by removable pins g, g, on withdrawing which that end of the bars is left free to be raised away from the roller.

For the purpose of adapting the machine 100 to different quantities of butter, it is necessary that the roller E, should be at different times, at different heights, above the butter board H. To accomplish this, I secure the rack pieces C, C, in head blocks 105 B, B, B, B, one situated against each of the four corner posts of the frame A, substantially as represented in the drawings. The bars D, D, are also located in notches h, h, h, h, in the upper ends of said head blocks, 110 and pivoted and secured therein as above set forth. These head blocks are made ad-

justable, up and down, against the posts of the frame A, by means of vertical slots b, b, b, b, in said head blocks, and screws a, a, a, a, extending through them into the frame 5 A, or by any other equivalent means. Thus, by loosening the screws a, a, a, a, the head blocks can be raised or lowered as much as desired; and then secured by again tightening the screws, thereby accomplishing the 10 object desired, substantially as shown and indicated in Fig. 3.

The butter is turned and shifted upon the butter board as often and as much as desired. But it is very desirable, if not absolutely necessary, to provide an automatic arrangement for shifting the relative position of the butter to the roller E, at every movement of the latter forward or backward. Otherwise, the ridges i, i, will continually travel in the same channels formed in the butter, and thus produce but very little effect, unless the position of the butter is continually shifted by hand—a tedious and laborious operation. In order to effect this 25 automatic shifting of the butter beneath the flutes of the roller E, I give to the butter board H, a side play, or room for movement, equal, say, to one half of the distance between the adjacent flutes of the roller. Then 30 two sides p, p, or their equivalents project upward from the butter board, so that the roller will strike them alternately,

at the close of each forward and backward movement. The effect is, that the roller first moves the butter board one way, and then 35 the other way, a distance equal to the extent of play allowed thereto; and thus to present the ridges i, i, of the roller to the ridges of the butter beneath, at every successive movement of the roller, and make new indentations therein. This movement is indicated by dotted lines in Fig. 2. The means of accomplishing this is seen to be exceedingly simple, as well as effective.

What I claim as my invention and desire 45 to secure by Letters Patent, is—

1. The combination and arrangement of the fluted roller E, and the butter board or table H, provided with sides or projections, p, p, so as to produce an automatic shifting 50 of the roller upon the butter at every turn of its movement, substantially as and for the purpose herein specified.

2. The adjustable head blocks B, B, B, B, arranged and operating in connection with the other parts of the machine, so as to adjust the roller E, to any desired height above the butter board or table H, substantially as herein set forth.

P. G. WOODARD.
